US00D559366S

(12) **United States Design Patent** (10) **Patent No.:** **US D559,366 S**
(45) **Date of Patent:** **** Jan. 8, 2008**

(54) **SINK**

(75) Inventor: **Jonathan C. Chong**, Chicago, IL (US)

(73) Assignee: **Elkay Manufacturing Company**, Oak Brook, IL (US)

(**) Term: **14 Years**

(21) Appl. No.: **29/272,226**

(22) Filed: **Feb. 2, 2007**

(51) **LOC (8) Cl.** **23-02**

(52) **U.S. Cl.** **D23/290**

(58) **Field of Classification Search** D23/271-274, D23/284-293.1, 303, 308; 4/619, 624, 661
See application file for complete search history.

(57) **CLAIM**

The ornamental design for a sink, as shown and described.

DESCRIPTION

FIG. 1 is a perspective view taken from the top, front, and right side of a sink showing my new design;

FIG. 2 is a top plan view of the sink shown in FIG. 1;

FIG. 3 is a bottom view of the sink shown in FIG. 1;

FIG. 4 is a front elevational view of the sink shown in FIG. 1;

FIG. 5 is a rear elevational view of the sink shown in FIG. 1;

FIG. 6 is a left elevational side view of the sink shown in FIG. 1;

FIG. 7 is a right elevational side view of the sink shown in FIG. 1;

FIG. 8 is a perspective view taken from the top, front, and right side of a second embodiment of a sink showing my new design;

FIG. 9 is a top plan view of the sink shown in FIG. 8;

FIG. 10 is a bottom view of the sink shown in FIG. 8;

FIG. 11 is a front elevational view of the sink shown in FIG. 8;

FIG. 12 is a rear elevational view of the sink shown in FIG. 8;

FIG. 13 is a left elevational side view of the sink shown in FIG. 8; and,

FIG. 14 is a right elevational side view of the sink shown in FIG. 8.

The broken lines are for illustration purposes only and form no part of the claimed design.

1 Claim, 14 Drawing Sheets
